UNITED STATES PATENT OFFICE.

ALFRED GRIFFITHS, OF ROCK FERRY, ENGLAND, ASSIGNOR TO KLEENGLAS LIMITED, OF LONDON, ENGLAND, A BRITISH COMPANY.

MEANS FOR WASHING, DRYING, AND POLISHING TUMBLERS, CUPS, AND LIKE ARTICLES.

Application filed February 2, 1928, Serial No. 251,439, and in Great Britain October 19, 1927.

This invention has for its object to provide improved means for washing, drying and polishing domestic utensils such as tumblers, cups, basins, and like hollow ware.

5 The invention relates more particularly to machines of the type in which india-rubber pads or squeegees are fitted upon parts carried by a rotatable head, the pads being pressed into contact with the inside and outside of the utensil being washed, dried and polished.

The invention comprises the improved combination and arrangement of parts as hereinafter described and claimed.

10 Referring to the accompanying sheet of explanatory drawings:—

Figure 1 is a side elevation, partly in section, Figure 2 a plan view of Figure 1, Figure 3 an end view looking from right to left of Figure 1, and Figure 4 a sectional end elevation looking from left to right and substantially on the line 4—4 of Figure 1, but with a glass in position, showing a glass cleaning or polishing machine in accordance 25 with my invention.

Figure 5 is a sectional elevation through a glass being cleaned in the machine.

Figure 6 is an end view looking from left to right of Figure 5 showing the cleaning 30 squeegees within the end of the glass.

Figures 7, 8, 9 and 10 illustrate the squeegees in section and elevation.

Figure 11 is an elevation and Figure 12 a plan of the part to which an inner squeegee 35 is secured.

Figure 13 is an elevation and Figure 14 a plan view of a spring which acts on the squeegee plate shown in Figures 11 and 12.

Figure 15 shows a modified arrangement 40 for cleaning the end of the interior of the glass.

The same reference letters in the different views indicate the same or similar parts.

Each pad or squeegee *a* comprises a rubber base reinforced with a metal plate *b* adapted to be secured upon the plate or the like *c* rotated by the machine as hereinafter described and a projecting strip *d* integral with *b* but at an angle to the base. The operative edge of the strip *d* is at right angles or substantially at right angles to the direction of projection of the strip and is of substantial thickness with square edges. The

tumbler or vessel *e* is forced between the squeegees to the position shown in Figure 5 with the strip *d* facing in the direction in which the head carrying the squeegees is rotated, (the tumbler or vessel being held by the hand in a stationary position). The resistance of the vessel to the movement of the 55 squeegees causes each strip *d* to turn over upon itself as shown in Figure 4, and the square edge of the strip to grip the vessel surface, whereby a very efficient and rapid cleansing, drying and polishing can be 60 effected.

The plates *c* carrying the squeegees which operate on the inside of the vessel *e* are secured to the central stem *f* by which they are rotated so that they can roll or adjust 70 themselves to suit the surface with which they contact. In the illustrated form, each plate *c* has a lug like member *g* thereon which enters a slot in the central stem *f*, the lug being a good fit in the slot in the 75 direction of rotation of the head but having rounded edges in the opposite direction (see Figures 1, 5 and 11) to permit of free rolling or turning movements of the plate. A screw *h* passing through a hole *i* in the lug 80 permits free movements of the latter whilst preventing its detachment. Each plate *c* carrying an inner squeegee is resiliently pressed away from the central stem by a plate or laminated spring *j* having ball like 85 parts *k* at its ends which enter the slots *m* in the plate and having a ball *n* also at its centre which enters a hole in the stem *f* and serve to locate the spring *j* during the rolling movements of the plate *c* and squeegee 90 thereon as the latter adjusts itself to the shape of a vessel being operated upon. The use of blade springs as *J* ensures an even pressure upon the vessel surface during 95 operation. The plates *c* carrying the squeegees may be made of such thinness that they can bend to suit special shapes of glasses, such as barrel glasses, if this be necessary.

The squeegees for the outsides of the vessels are carried by plates fulcrumed upon arms *o* pivoted at *p* to brackets *q*, springs *r* tending to turn the arms so as to press the said outer squeegees towards the inner ones.

The inner and outer squeegees and the 105 parts by which they are carried are so ar-

ranged that centrifugal force due to the rotation of the device tends to force the squeegees into firmer contact with the vessel surface.

5. The ends of the squeegees which act within the vessel being cleaned may project outwards beyond the plates *c* to a sufficient extent and be shaped to clean also the bottom of the vessel as shown in Figures 5 and 6. Or a 10 squeegee like head *s* (Figure 15) may be attached to the rotating stem *f* for the same purpose. Such head may be shaped differently for different shapes of vessels. Spring pressure may hold the head in firm contact 15 with the vessel during cleaning or the like.

For washing or cleaning a vessel, water mixed if desired with disinfectant is introduced through the apertures *t* in the rotating stem (which is tubular) into the vessel, but 20 for drying and polishing, the same construction of head may be employed but no liquid is introduced.

In use, a tumbler or glass to be cleaned is 25 pressed between the inner and outer squeegees and held by the hand whilst the complete device upon the base *u* is rotated. Liquid from the apertures *t* facilitates the cleansing operation. After a short period, the tumbler or glass may be withdrawn and 30 be polished by a similar device running dry.

What I claim is:—

1. In a device of the kind described, the combination of, a rotating head, and squeegees upon said head, each squeegee consisting of a rubber base with a projecting strip, the strip projecting in the direction in which the head is rotating, as set forth.

2. In a device of the kind described, the combination of, a rotating head and squeegees upon said head, each squeegee consisting of a rubber base with a projecting strip, the edge of the strip being at right angles 40 to the direction of projection of the strip

which is in the direction in which the head rotates.

3. In a device of the kind described, the combination of a rotating head and squeegees upon said head, each squeegee consisting of a rubber base with a metal reinforcement thereon, a strip upon and at an angle 45 to said base, the strip projecting in the direction in which the head rotates, the operative end of the strip having a square edge, and being substantially at right angles to the direction in which the strip projects. 50

4. Means for washing, drying and polishing tumblers, cups and like articles comprising, in combination a hollow perforated stem, two plates secured to said stem at opposite sides, means allowing the plates to have a rolling movement about their securing means, a squeegee secured to each plate and two pivotally mounted squeegee carrying plates opposed to the squeegees before referred to, as set forth. 55

5. In a device of the kind described, the combination of, a rotatable base piece, a central hollow stem upon said base piece, two squeegee carrying plates having lugs thereon extending into slots in and from opposite sides of said stem, plate springs interposed between said stem and said plates, with means for locating the springs upon 60 said stem, securing means for the plates passing through holes in the plate lugs and fastened in the stem, levers pivoted upon the base at opposite sides, squeegee carrying plates on said levers, the four squeegees coming together in two pairs so that the article to be cleaned can be held on its inside and 65 outside by said squeegees, and resilient means acting upon the levers to force the outer squeegees towards the inners.

In testimony whereof I have signed my name to this specification.

ALFRED GRIFFITHS.
